[57] CLAIM

The ornamental design for a volt-ohm-ammeter or the like, as shown and described.

DESCRIPTION

FIG. 1 is a top, front, and right side perspective view of a volt-ohm-ammeter or the like showing my new design;

FIG. 2 is a right side elevational view;

FIG. 3 is a top plan view;

FIG. 4 is a bottom plan view;

FIG. 5 is a left side elevational view;

FIG. 6 is a front elevational view; and

FIG. 7 is a rear elevational view thereof.

FIG. 1

FIG. 2

FIG. 3

FIG. 4

FIG. 5

FIG. 7

FIG. 6
